TRAFFIC SIGNAL SYSTEM

Filed Nov. 19, 1928

UNITED STATES PATENT OFFICE

CHANCY F. WHITNEY, OF SCOTIA, NEW YORK, ASSIGNOR TO GENERAL ELECTRIC COMPANY, A CORPORATION OF NEW YORK

TRAFFIC SIGNAL SYSTEM

Application filed November 19, 1928. Serial No. 320,247.

My invention relates to traffic signal systems and more particularly to improved means whereby traffic signals which are utilized at street intersections may be operated in response to sound produced on vehicles.

Means are now known whereby traffic signals which are utilized at the intersection of a main street and a side street may be adjusted normally to produce safe signals on the main street and danger signals on the side street and controlled in response to the sound of the horn on a vehicle on the side street, the operator of which wishes to gain admission to the main street. In response to the sound of the horn the signals are operated through the usual cycle of operations including a safe signal to traffic on the side street and a danger signal to traffic on the main street and are then returned to the normal condition of safe on the main street and danger on the side street.

In systems of this kind it is necessary that means be provided whereby when the cycle of operations has once been started it cannot be interfered with by subsequent sounding of horns on the side street until the signals have returned to the normal condition and a safe signal on the main street and a danger signal on the side street have been maintained for a predetermined period of time. It is also desirable that a signal be given to the vehicle operator who has sounded his horn during this predetermined period of time thereby to gain admission to the main street to inform him that the equipment has responded to the sound of his horn and that the signals will change after this predetermined period has terminated.

One of the objects of my invention is to provide means whereby these results may be accomplished which are of more simple construction and of more reliable operation than systems of known form. Another object of the invention is to provide means whereby the warning signal which is commonly used to indicate that a change in signals is about to occur may also be utilized as an indication to the operator that the sound of his horn has been registered by the equipment and that the

lights will change after a predetermined time interval.

Still another object of the invention is to provide means whereby the traffic signals may be operated not only in response to sound produced by vehicles on the side street but whereby the signals may also be operated by pedestrians who desire to cross the main street.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which the single figure represents an embodiment of my invention.

Referring to the drawing 1 and 2 represent respectively the signal housings which are mounted upon the main and side streets in the usual manner. Each of these housings includes a danger signal R, a caution signal A, and a safe signal G, these letters being indicative of the colors red, amber and green which are commonly employed.

In accordance with the system to be disclosed these signals are controlled by means of a timing mechanism or controller 3 which is of well known construction, such as, for example, that shown in Patent No. 1,851,246, granted March 29, 1932 to Chester I. Hall, and this timing mechanism is in turn controlled responsively to sound produced upon vehicles upon the side street. The means whereby this result is accomplished comprise microphones 4, which are mounted upon the side street at either side of the intersection and which serve to control the current flowing in the anode circuit of an electron discharge device 5 which in turn controls relays 6 and 7.

To explain the operation of the system I will first indicate the operation of the timer, or controller, 3. This timer is of well known construction and its structure need not be other than generally explained in the present application. It comprises a motor mechanism comprising an induction disk 8 and field windings 9. These field windings are normal-

ly energized from an alternating current supply circuit 10 to which they are connected through conductors 11 and 12. The disk 8 serves to drive the shaft 13 in a counterclockwise direction through a chain of gears 14. The shaft 13 carries a plurality of cams 15, 16, 17, 18 and 19 which cams are arranged in spaced relation with respect to each other and cooperate with levers 20 and 21 to control 10 the position of a non-conducting member 22. This member 22 serves to operate contact fingers 23, 24, 25 and 26, which fingers in turn control the position of the signal lamps R, A and G. Each of these contact fingers 15 operate with a stationary contact, all of which are connected together and to one side of the supply circuit 10 through conductors 27 and 28.

With the induction disk motor 8, 9 in the 20 position shown in the drawing, it will be seen that contact finger 25 only is in engagement with its stationary contact. A circuit is completed which extends from one side of the supply circuit 10 through conductor 28, contact finger 25, conductor 29, lamps G on the main street and R on the side street, and conductor 30 to the opposite side of the supply circuit. Thus normally the lamp G provides 25 a safe signal upon the main street and the lamp R a danger signal upon the side street.

The motor 8, 9 is normally restrained in this 30 position by means of a brake magnet 31. Brake magnet 31 has an armature 32 which swings about a pivot 33 and which carries 35 near its outer end a lever 34. The lever 34 swings about a pivot 35 and is arranged such that when the magnet 31 is energized, a projecting foot 36 on the lever 34 engages the disk 8 and the opposite end of the lever 34 40 falls within the path of travel of a stud 37 mounted upon a cam 38 which is carried by the shaft 13. Normally the stud 37 is in engagement with the lever 34 and bearing down thereon presses the foot 36 into engagement 45 with disk 8 thereby restraining the disk and shaft 13 against rotation. This brake magnet 31 is energized through a circuit which extends from one side of the supply circuit 10 through conductor 11, actuating winding 50 of the brake magnet 31, upper stationary contact and armature of relay 7 to the opposite side of the supply circuit 10. Relay 7 is normally connected across the supply circuit 10 through the armature and upper stationary 55 contact of relay 6, which relay is included in the anode circuit of an electron discharge device 5.

The electron discharge device 5 is of the 60 usual three-element type having a condenser and grid-leak combination 39 connected in the grid circuit thereof, in series with the secondary winding of a microphone transformer 40. The primary winding of this transformer is included in circuit with a smooth- 65 ing condenser 41 and the microphones 4. A

direct current potential is impressed upon the condenser 41 by means of a transformer 42, the primary of which is connected to the supply circuit and the secondary 43 of which supplies potential through a rectifying unit 45 to the condenser 41. This rectifying unit 70 may be of any suitable form but preferably is comprised of rectifiers of the type shown in United States Patent No. 1,640,335 to Lewis O. Grondahl issued August 23, 1927. The 75 anode circuit of the electron discharge device 10 extends from the upper side of the supply circuit 10 through the space between the cathode and anode of electron discharge device 5, winding of relay 6, armature and upper contact of relay 6 to the opposite side of the supply circuit. 80

With the apparatus in the position shown in the drawing, let us assume that an operator, desiring to gain admission from the side 85 street to the main street, sounds his horn. The microphones 4 operate and in a well known manner act upon the grid of the device 5 to diminish the current flowing in the anode circuit of that device. Relay 6 is deenergized and its armature is actuated into engagement with its lower contact thereby interrupting the anode circuit of device 5 and deenergizing relay 7. The armature of relay 7 is then actuated to its lower position 90 thereby deenergizing the brake magnet 31, which in turn releases its armature and thereby permits the motor 8, 9 to drive the cam shaft 13 in a counterclockwise direction. At the same time the armature of relay 7 completes an indicating circuit which extends from one side of the supply circuit 10 through the armature and lower contact of relay 7, conductor 46, signal lamp A in the housing 100 2 on the side street and conductor 30 to the 105 opposite side of the supply circuit 10. The lighting of the signal lamp A indicates to the operator that his signal has been registered, and that after a predetermined interval of time the signals will change. 110

Upon rotation of the shaft 13 through a predetermined arc it will be seen that the lever 21 which rides upon cam 17 will drop down upon cam 19 and in so doing the member 22 carried by the lever 21 will be moved forward. This movement will be sufficient to cause finger 25 to be actuated out from engagement with its stationary contact and fingers 23 and 24 to be actuated into engagement with their stationary contacts. Finger 23 will cause lamp A on the main street to be lighted. While finger 24 is connected, in this position, in circuit with the caution lamp A on the side street it will have no operation at this time since this lamp is already lighted. 120 Upon further rotation of the shaft 13 the lever 21 will drop from cam 19 on to cam 18 and thereby move member 22 a second step forward. In this position contact finger 26 will be actuated into engagement with its 125 130

stationary contact and will thereby cause the energization of the danger lamp R on the main street and the safe lamp G on the side street. At the same time this finger will 5 again complete the anode circuit of discharge device 5 and energize relay 6. This circuit extends from one side of the supply circuit 10 through conductor 28, finger 26, lower stationary contact and armature of relay 6, actuating winding of relay 6, anode and cathode of electron discharge device 5 to the other side of the circuit 10. Relay 6 will now 10 again be energized and will actuate its armature to the normal position thereby again energizing relay 7 which in turn actuates its armature to the normal position. In this position these relays are maintained energized through the armature and upper contact of relay 6. Brake magnet 31 is now again 15 energized and actuates its armature 32 and lever 34 to the position shown in the drawing. However, since the stud 37 is not now in the position shown in the drawing the foot 36 of lever 34 will be held away from disk 8 by 20 spring 50 and, hence, will not stop the rotation of the disk. With the controller in this position contact fingers 23 and 24 are both moved out from engagement with their stationary contacts, and, accordingly, the caution 25 signals A on both the main and the side streets are extinguished.

The lever 20 which is now riding upon cam 16 will, after a further rotation of the shaft 16, drop down upon the portion 48 of cam 35 15. Upon this movement the upper end of lever 20 will engage lever 21 and thereby operate the member 22 into the position where caution signals were given. In this position fingers 23 and 24 are in engagement with 40 their stationary contacts, and thereby energize the caution signals, while fingers 25 and 26 are both out from engagement with their stationary contacts. When the period for caution signals has terminated the lever 45 20 will drop from the portion 48 of the cam 15 on to the portion 49 of that cam, and will thereby operate the member 22 back to the position shown in the drawing, thereby extinguishing the caution signals and again 50 lighting the safe signals on the main street and the danger signals on the side street. After these signals have been maintained for a predetermined interval of time the stud 37 will again engage the end of shaft 34. Since 55 the magnet 31 is now energized the lever 34 will fulcrum about the point 35, and thereby bring pressure upon the disk 8 sufficient to stop the motor. The signals will then be maintained in this position until the microphones 4 again respond to sound produced 60 upon a vehicle.

It will be seen that after the motor 8, 9 has been released by deenergizing the brake magnet 31 in response to sound, the foregoing 65 cycle of operations will ensue and that no

interference can result from any subsequent sounding of horns upon the side street. During the cycle of operations the period of each of the different signals is determined entirely by the controller. When the safe signal on the main street and the danger signal on the side street have been restored the controller is stopped by engagement of stud 37 with the lever 34 and these signals are maintained until subsequent actuation of the controller in response to sound produced on the side street. If, prior to this engagement one of the microphones 4 is actuated, it will be seen that the caution light A on the side street will be lighted informing the vehicle operator that the sound of his horn has been registered. The magnet 31 will also be deenergized but the safe signal will be continued for the predetermined interval which is determined entirely by the controller. When this interval is terminated, due to the fact that the magnet 31 is deenergized, the stud 37 will not engage the member 34, and, accordingly, another revolution of the shaft 13 will follow, thereby causing a subsequent cycle of operations.

To provide means whereby pedestrians upon the side street may obtain the right of way to cross the main street a key 51 is inserted in the microphone circuit. This key will preferably be mounted in convenient reach of the pedestrian at the street corner, and if desired one key may be provided at each corner and all arranged to interrupt or vary the current in the microphone circuit. When the pedestrian opens the contacts of key 51 the current in the microphone circuit is interrupted thereby producing, through transformer 40, a voltage impulse upon the grid of device 5. This impulse will cause the above cycle of operations to ensue.

While I have mentioned the use of my invention particularly in the operation of traffic signals at street intersections it will of course be understood that it has utility in other fields, as, for example, in railway signaling. Further, while I have described a particular cycle of operations, it will be understood that this cycle of operations, is determined entirely by the controller and may be varied as desired.

While I have shown a particular embodiment of my invention, it will of course be understood that I do not wish to be limited thereto since many modifications, both in the circuit arrangement and in the instrumentalities employed, may be made without departing from the spirit and scope of my invention, as set forth in the appended claims.

What I claim as new and desire to secure by Letters Patent of the United States, is:

1. In a signal system for intersections of main and side streets, comprising a danger signal on the main street and safe and danger signals on the side street, a controller arranged for rotation, means tending to rotate

- said controller, means for restraining said controller against rotation including a normally energized brake magnet, an electron discharge device having an anode circuit including a relay, means responsive to sound produced on the side street for supplying impulses to said discharge device thereby to operate said relay, connections controlled by said relay when operated for deenergizing 10 said brake magnet thereby to release said controller and for interrupting said anode circuit, connections between said controller and said signals, whereby after said controller is released the signals on the side street are 15 changed from danger to safe and then to danger, and said danger signal on the main street is operated simultaneously with the safe signal on the side street and means responsive to operation of the controller to a 20 predetermined position for completing said anode circuit thereby to restore said relay and brake magnet to the normal condition.
2. In a signal system for main and side street intersections, comprising a danger 25 signal on the main street and safe, danger and caution signals on the side street, a relay having normally closed and normally open contacts and an energizing circuit, means responsive to sound produced on the side street 30 to interrupt said energizing circuit, a circuit for said caution signal including said normally open contacts, a controller arranged for rotation, means for restraining said controller in a predetermined position against 35 rotation, said means including a magnet having a holding circuit including said normally closed contacts, whereby in response to said sound on said side street said caution signal is energized through said normally open contacts and said magnet is deenergized, connections between said controller and said signals whereby said caution, safe and danger signals are operated through a predetermined cycle of operations when said controller is released, 40 and means responsive to operation of the controller to a predetermined position to complete said energizing circuit of said relay and thereby cause deenergization of said caution signal and energization of said magnet.
- 50 3. In a signal system for main and side street intersections, comprising a danger signal on the main street and safe and danger signals on the side street, an electron discharge device, a relay having a winding and 55 contacts included in said anode circuit, means including said electron discharge device whereby sound produced on the side street is caused to operate said relay thereby to interrupt said anode circuit, a controller arranged 60 for rotation, means for restraining said controller in a predetermined position against rotation, said means including a magnet, a second relay, means to control said second relay in accordance with the operation of said 65 first relay, said second relay having contacts
- in circuit with said magnet, means comprising said contacts whereby said controller is released upon operation of said second relay, connections between said controller and said signals whereby when said controller is released said signals are operated through a cycle of operations, means including said first relay responsive to operation of said controller to a predetermined position for again completing said anode circuit whereby said first relay is energized and said second relay is operated to restore said magnet to the initial condition. 70
4. In a signal system for main and side street intersections, comprising a danger signal on the main street and safe, danger, and caution signals on the side street, an electron discharge device, a relay having a winding and contacts included in said anode circuit, means including said electron discharge device whereby sound produced on the side street is caused to operate said relay, thereby to interrupt said anode circuit, a controller arranged for rotation, means for restraining said controller in a predetermined position against rotation, said means including a magnet, a second relay, means comprising connections to control said second relay in accordance with the operation of said first relay, said second relay having contacts in circuit with said caution signal and said magnet, means comprising said contacts whereby said controller is released upon operation of said second relay, and said caution signal is simultaneously energized, connections between said controller and said signals whereby when said controller is released said signals are operated through a predetermined cycle of operations, means including said first relay responsive to operation of said controller to a predetermined position for again completing said anode circuit whereby said first relay is energized and said second relay is operated to restore said magnet to the initial condition and said caution signal is deenergized. 80
- In witness whereof I have hereunto set my hand this 17th day of November, 1928.
